UNITED STATES PATENT OFFICE

136,270

DESIGN FOR A LOCKET

Thomas H. Massey, Smithfield, Va.

Application January 19, 1942, Serial No. 105,312

Term of patent 3½ years

To all whom it may concern:

Be it known that I, Thomas H. Massey, a citizen of the United States, residing at Smithfield, in the county of Isle of Wight and State of Virginia, have invented a new, original, and ornamental Design for a Locket, of which the following is a specification, reference being had to the accompanying drawing, forming a part thereof.

I claim:

The ornamental design for a locket, as shown.

THOMAS H. MASSEY.
